UNITED STATES PATENT OFFICE.

TIMOTHY G. DALY, OF BOSTON, MASSACHUSETTS.

WATCH-GUARD.

SPECIFICATION forming part of Letters Patent No. 358,020, dated February 22, 1887.

Application filed December 2, 1886. Serial No. 220,488. (No model.)

To all whom it may concern:

Be it known that I, TIMOTHY G. DALY, of Boston, in the county of Suffolk, State of Massachusetts, have invented a certain new and useful Improvement in Watch-Guards, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved guard represented as in position for use; Fig. 2, a like view showing the guard attached to a watch and in position for use; Fig. 3, an enlarged side elevation of the guard detached; Fig. 4, an enlarged front elevation of the same; Fig. 5, an enlarged vertical section of the same, the loop being shown in side elevation; Fig. 6, a like view showing the springs depressed and the flukes extended; and Fig. 7, a bottom plan view of the guard, enlarged, above the line $x-x$, the base being represented as removed.

Like letters of reference indicate corresponding parts in the different figures of the drawings.

My invention relates more especially to that class of watch guards or protectors which are designed to prevent the pickpockets from extracting the watch from the pocket when in use.

It consists in a novel construction and arrangement of parts, as hereinafter more fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the guard, and B the flukes or spurs. The body, which is preferably composed of metal, is made hollow and provided with a groove or depression, y, adapted to receive the ring z of the watch W. A loop, H, is disposed in the body A, the arms c c passing through holes h in the top thereof on either side of the groove y, the ends of the arms being bent to form eyes d.

The body A is hollow and provided on two of its sides, near the base, with a hole, m, open-

ing into its interior. A plate, D, comprising two upwardly-projecting flukes or spurs, B, and having its lower end bent nearly at right angles to its body to form the arm i, is inserted in each of the holes m, a hole or slot, v, being formed in each of the arms i, through which the respective arms c of the loop H pass.

Disposed within the body A, around each of the arms c of the loop H, there is a coiled spring, t, one end of which rests on the inwardly-projecting arm i of the plate D and the other against the top of said body, said springs acting expansively to force the arms i downwardly into a horizontal position and the flukes B upwardly into a vertical position, or to keep said flukes folded against the sides of the body A. Disposed in each of the eyes d of the arms c there is a ring, r, to which the ordinary swivel, E, of the chain J is attached.

In the use of my improvement the ring z of the watch W is inserted in the groove y between the arms c c of the loop H, and the chain J attached to the rings r r by means of the swivel E, or in any other suitable manner, the opposite end of the chain being secured to a garment and the watch inserted in a pocket, in the usual manner. The watch being in the pocket and the chain secured, as described, if, now, the chain is pulled to withdraw the watch, the loop H and arms i of the plate D will be drawn upwardly, causing the spurs or flukes B to be projected laterally and engage the sides of the pocket, thereby preventing the watch from being withdrawn therefrom, in a manner which will be readily obvious without a more explicit description. When the chain is released, the springs t will force the arms i downwardly in the body A and cause the flukes B to be folded again. When it is desired to remove the watch from the pocket without causing the flukes B to be projected, as described, the watch may be grasped by the ring or stem; or the guard may be so grasped between the fingers as to prevent the flukes from being projected.

It will be understood that in use the guard is to be so disposed as to be inserted in the pocket with the watch. The swivel may, however, be so arranged as to be connected directly with the ring of the watch, as shown in Fig. 1, in which case a ring, l, may be employed to connect the chain with the rings r r

of the guard. It is preferable, however, to connect the ring of the watch directly with the guard, as shown in Fig. 2.

Having thus explained my invention, what I claim is—

1. The combination of a hollow body or casing provided with lateral openings, tilting or folding flukes at the sides of said body, provided with inwardly-projecting slotted arms passing through said openings, a sliding U-shaped loop within said casing, the arms of said loop passing through the slots in the arms of the flukes, their outer ends projecting through the casing at the upper end thereof, and springs surrounding the arms of said loop between the upper end of the casing and the slotted arms of the flukes, substantially as described.

2. The combination of a hollow body or cas-

ing provided with lateral openings, tilting or folding flukes at the sides of said body, provided with inwardly-projecting slotted arms passing through said openings, a sliding U-shaped loop within said casing, the arms of said loop passing through the slots in the arms of the flukes, their outer ends projecting through the casing at the upper end thereof, and springs surrounding the arms of said loop between the upper end of the casing and the slotted arms of the flukes, said casing being provided with a recess for the watch-ring between the arms of said loop, substantially as described.

TIMOTHY G. DALY.
